FIG. 1 is a perspective view of the protective housing for service meters showing our new design;

FIG. 2 is a frontal view of the protective housing for service meters shown in FIGURE 1;

FIG. 3 is a side view partially in section of the protective housing for service meters shown in FIGURE 1.

The broken line portion is shown for illustrative purposes only.

The characteristic features of this design reside in a series of generally parallel ribs which extend along the interior of the cylindrical shield body, and the presence of an external shoulder at the juncture of the cylindrical shield body and the anchoring flange at its base.

We claim:

The ornamental design for a protective housing for service meters, as shown and described.
